UNITED STATES PATENT OFFICE

2,647,445

BEATER REFINER APPARATUS

Dwight E. Jones and Charles H. Vickery, Pittsfield, Mass., assignors to E. D. Jones & Sons Company, Pittsfield, Mass., a corporation of Massachusetts

Application December 2, 1950, Serial No. 198,888

5 Claims. (Cl. 92—24)

1

Our invention relates to new and useful improvements in apparatus for processing material for forming paper, pulp, and the like and is directed more particularly to a beater-refiner mechanism.

The principal objects of the invention are directed to a novel and improved construction of beater-refiner mechanism which is constructed and arranged as a unitary and self-contained structure adapted for shipment as a unit or package for installation at the mill.

Heretofore the several components of beater apparatus have been machined, fitted and assembled at the place of manufacture and then disassembled for the shipment of the separate units to the mill where they were reassembled. For instance, it has been usual to ship as separate such units as each stand and lighter-bar, the cross or equalizer shaft, the links, the curb, the cover, the front side, the mid-side, the back fall, the motor support, the packing boxes, the roll, the bearings, and the bed plates, etc. At the mill where the beater is to be used, the units have been uncrated and assembled or erected and this has always necessitated the sending of skilled erectors to the plant of the purchaser which may be thousands of miles from the place of shipment.

The purchaser must provide foundations for the different components to which the components are secured. These foundations and securing means must be disposed accurately relative to one another in order to tie the units together in accurate relationship and alignment in order to withstand the shocks and strains resulting from the operation of the beater and maintain the necessary accurate relationship and alignment of the components for operation of the machine.

According to this invention, a complete unitary mechanism is provided wherein the components are assembled or erected in conjunction with supports and tub forming elements to provide a complete unitary structure adapted for shipment as a complete unit.

The unit may be shipped to the purchaser's plant and placed on a suitable support such as a foundation and is in readiness for operation without the usual erection or assembly. The components of the mechanism being assembled

2

with supporting structure and tied together in operative relationship provide a self-sustaining unit where the correct relationship and alignment of components is maintained. In this way, complicated foundation units to which the structure must be tied are unnecessary. In fact, the necessary tying together of the components is accomplished within the structure itself and all that is necessary at the purchaser's plant is a suitable support which may be a foundation or even a suitable floor structure. On this the mechanism is established and it need not necessarily be secured thereto since shocks, strains and forces in the operation of the mechanism are absorbed and compensated for within the unitary structure itself and are not, as with prior art structures, transmitted to the supports therefor.

As an example, with a prior art beater when the roll is in upper position, the load is transmitted to the externally mounted stands and when the roll is lowered most of the load is transferred to the bed plates so that due to the shifting of load it is necessary to securely anchor the unit to a foundation. With the present case, the transfer of load is not external to the unitary structure.

The purchaser may construct a beater tub of any desired form around and in connection with the mechanism. This feature offers a completely flexible arrangement in that the tub can be built of any type of material such as tile, concrete, steel or wood. Also the size of the tub can be readily altered to suit the space available or the demand which may be placed for a given batch.

If desired, the tub may be eliminated and the unitary mechanism set up for continuous processing of stock which is fed thereto at one end and delivered therefrom at the other, and plural mechanisms may be arranged in alignment without the tub construction for successive steps in the continuous processing of stuff.

By reason of the unitary construction, it is possible to provide a mechanism which is more efficient in operation and in which the components are at all times maintained in accurate relationship and alignment. Not only is the necessity of sending erectors for erecting apparatus obviated but the shipping difficulties with many separate units is avoided by the provision of the unitary structure.

As an important feature of the invention, manufacturing costs are greatly reduced. According to the invention, sheet metal is employed which is secured together as by welding to provide a strong rigid supporting structure for components mounted on and secured thereto. In this way costly machined castings are largely obviated.

All of the above objects I accomplish by means of such structure and relative arrangements of parts thereof, as will fully appear by a perusal of the description below and by various specific features which will be hereinafter set forth.

To the above cited and other ends and with the foregoing and various other novel features and advantages and other objects of my invention as will become more readily apparent as the description proceeds, my invention consists in certain novel features of construction and in the combination and arrangement of parts as will be hereinafter more particularly pointed out in the claims hereunto annexed and more fully described and referred to in connection with the accompanying drawings wherein:

Figs. 1 and 2 are front elevational and plan views showing beater-refiner mechanism embodying the novel features of the invention;

Fig. 3 is a vertical sectional elevational view through the housing of the lighter-bar adjusting mechanism;

Fig. 4 is a longitudinal sectional elevational view on the line 4—4 of Fig. 1;

Fig. 5 is a transverse sectional elevational view on the line 5—5 of Fig. 4;

Fig. 6 is a transverse sectional elevational view on the line 6—6 of Fig. 2;

Fig. 7 is a perspective view of one of the reinforcing members of the pillars;

Fig. 8 is a sectional elevational view on the line 8—8 of Fig. 2; and

Fig. 9 is a sectional plan view on the line 9—9 of Fig. 2.

Referring now to the drawings more in detail, the invention will be fully described.

A longitudinal front wall 2 and a longitudinal mid-wall 4, both vertically disposed, are provided. These will preferably be formed from metal plate or sheet material. Stainless steel has been found to be desirable for the practice of the invention as it is capable of withstanding the injurious action of the constituents of paper and pulp making materials.

The walls 2 and 4 are secured to metal transversely spaced longitudinal horizontal sole plates 6 and 8 and is preferably accomplished by welding as indicated at 7 and 9, in Figs. 5 and 6.

The rear wall 4, herein referred to as mid-wall, functions as the mid-feather when the unitary structure hereof is used by the purchaser in connection with a beater tub construction.

A transverse base plate 10 of metal is provided, see Fig. 4. This plate extends between walls 2 and 4 and at opposite sides is welded thereto thereby functioning to provide a base for the bed plate construction and to tie the walls 2 and 4 together. Said plate may be called the bed plate base.

Transverse partitions 12 above the plate 10 have opposite ends secured to the walls 2 and 4 and to said plate 10 as by welding.

An intermediate transverse substantially vertical plate 14 of metal has a lower end portion 16 and an upper portion 18 with its opposite ends secured to the walls 2 and 4. The lower edge of

portion 16 is welded as at 17 to the plate 10. The plate 14 may be called the back fall plate.

A lower transverse plate 20 has a depending portion 22 and the right hand end portion thereof is formed to provide a transverse channel 24. This member has opposite ends welded to the walls 2 and 4 and the lower edge of portion 22 is welded at 23 to the plate 10. This plate 20 may be called the front plate.

The plate portions 16 and 22 and partitions 12 provide a plurality of transversely extending pockets for bed plate boxes indicated by 25. These boxes may be of ordinary construction having a plurality of longitudinal cutter bars or knives 28 projecting from upper sides thereof.

The boxes 26 are insertable into the pockets through the front wall 2 which is provided with a suitable opening 29 closed by a cover plate 30 secured in place by screws or bolts 32, see Fig. 2. This is usual construction and permits of the boxes being inserted in and withdrawn from the pockets.

Reinforcing members 34 are welded to the member 10 and adjusting screws 36 in threaded engagement with the member 10 and members 34 engage the underside of the boxes 26 for adjusting them relative to the beater roll 40.

An opening 42 in wall 2 is provided for access to the adjusting members 36 and a cover 44 therefor is secured thereover by screws or bolts 46.

Pillars for lighter-bar pivots indicated generally by 50 are disposed on outermost sides of the walls 2 and 4, see Figs. 2 and 6. Said supports 50 are formed from sheet metal to be channel shape in cross section and have outer vertical sides 52, and opposite sides 54 and 56 adjacent thereto extending upwardly in converging relation from the sole plates 6 and 8.

The lower ends of the outer sides 52 are secured to the sole plates by welding at 53. Lower ends of sides 54 and 56 are similarly welded to the sole plates and the rear vertical edges of said walls 54 and 56 are welded to the walls 2 and 4.

Transversely spaced and vertically extending pivot supports 60 and 62 provided at the upper sides of the pillars and horizontal cap plates 64 are welded to the supports 60 and 62 and walls 2 and 4 while the supports 60 are welded to portions 52 of the pillars as best shown in Fig. 6.

Pivots 68 are journaled in the supports 62 and 60 by antifriction bearings 70 while caps 72 are disposed at opposite ends of the said pivots.

Reinforcing members 76 and 78 are provided which extend from the sole plates into the pillars. Said members are U-shaped and substantially alike, the member 76 being shown in Fig. 7. Said members have upwardly extending arms such as 80 as in Fig. 7 which extend within the walls of the pillars 50. Lower portions of the reinforcing members are welded to the sole plates and the side arms thereof are welded to the walls of the pillars and upper supports thereof.

The pillars are filled with concrete indicated by 82 which with the fabricated members provide strong rigid structures suitable for pivotally supporting the lighter-bars carrying the roll 40.

These pillars 50 are integral parts of the structure and obviate the foundations heretofore necessary for supports for the lighter-bars in the necessarily correct relationship to similarly supported other components.

Lighter-bars 84 are provided which have inner ends 86 on said pivots 68. The said inner ends of the lighter-bars may be fixed on the pivots which

are oscillatable in the bearings or the pivots may be fixed in the members 60 and 62 with the said lighter-bars oscillatable thereon.

The lighter-bars adjacent the pivots are provided with caps 88 secured thereto and which retain anti-friction bearings 90. End caps 92 close outer ends of the bearings and inner ends are provided with suitable sealing means indicated by 94.

Shaft ends 96 of the roll 40 are journaled for rotation in the bearings 90. The roll 40 may be of any suitable form having knives or cutter bars 98 for cooperating with the knives or cutter bars of the bed plate although the roll of U. S. Letters Patent No. 2,482,712 of September 20, 1949 has been found to be very desirable for the practice of the invention.

The lighter-bars 84 are swingable up and down to vary the position of the roll and its cutter bars relative to those of the bed plate, by mechanism 20

A hood or cover 100 overlying the roll has flanges 102 and 104 at its sides and ends. The side flanges rest on flanges 106 of the walls 2 and 4 and are secured thereto by suitable means, such as bolts.

A curving wall 108 extends between walls 2 and 4 partly around the roll 40, see Fig. 4. This wall may be termed a breast plate and has a flange 110 on its upper end to which the flange 104 of the cover is secured, as shown in Fig. 4.

Annular members 112 extend from opposite ends of the roll 40 and have fixed thereto flexible sealing discs 114 which engage members 116 secured to opposite sides of the cover 100 around openings 118 therein, see Fig. 5. The construction is such as to permit rotation and up and down movements of the roll 40 whilst sealing the roll and cover.

Links 120 are pivoted at 122 to the forward ends of the lighter-bars 84 and upper ends of said links are pivoted at 124 to arms 126 of a transverse equalizer shaft 128. Bearing supports such as 130, are secured to the walls 2 and 4 by means of a ring 132 and bolts 134, see Fig. 8. Shaft 128 is rotatable in anti-friction bearings 134 in the supports 130 and annular caps 136 close said supports.

The arms 126 are fixed to opposite ends of the equalizer shaft 128 and the arrangement is such that the lighter-bars swing uniformly or through the same angle as one or the other of them is actuated. In this way since the lighter-bars move uniformly by means of shaft 128, the axis of roll 40 is maintained on a horizontal axis at all times.

Means for actuating or adjusting the lighter-bars disposed adjacent the wall 2 will be explained with reference to Figs. 2 and 3.

A stand 140 is secured to the sole plate 6 and and adjusting screw 142 is reciprocable therein. A worm gear 144 is rotatable in a housing 146 at the upper end of the stand 140 and a worm 148 in engagement therewith is fixed on a shaft 150 which is rotatable in the said housing and carries a hand wheel 152 on its outer end.

The gear 144 is in threaded engagement with the screw 142 and the upper end of the screw carries a piston 154 disposed in a cylinder 156. The upper end of the cylinder is pivoted at 158 to the lighter-bar 84 adjacent the forward wall 2.

Adjustment of the lighter bar may be accomplished by means of the hand wheel which through the screw causes the piston to impart motion to the cylinder or in another way pressure may be applied between the piston and upper end of the cylinder for actuating the lighter-bar.

As will be observed, the adjusting mechanism is integral with the structure and is maintained in accurate operating relationship and is advantageous as with prior art practice the mechanism is mounted on a foundation or support and relationship and alignment of components is difficult.

Left hand end portions 160 of the walls 2 and 4 extend upwardly and on outer sides are provided with pilasters 162 and a supporting platform 164 thereabove, see Figs. 1, 2 and 9.

The pilasters are U-shaped in horizontal cross section and have outer vertical sides 166 and adjacent vertical sides 170 and 172. These pilasters are formed from sheet metal and lower ends are welded to the sole plates 6 and 8. Vertical edges of the parts 170 and 172 are welded to the walls 2 and 4. Upper ends of the pilasters are welded to the horizontal platform 164.

Thus there is provided a strong rugged support for driving mechanism which in the form of the invention shown, consists of a motor 180 secured to a sub-base 182 which in turn is secured to the platform 164.

A shaft 184 of the motor has a grooved wheel 186 for a plurality of belts fixed thereto and a driven grooved wheel 188 is fixed to the roll shaft 96. A plurality of endless driving bands or belts 190 engage the pulleys 186 and 188 whereby the roll is driven by the motor.

The axis of the lighter-bar pivots, axis of rotation of roll 40 and axis of motor shaft 184 are so disposed that the driving tension of the bands is not affected by up and down adjustments of the roll relative to the bed plate. That is, the longitudinal axes of the roll, motor shaft and pivot of the lighter bars are in substantially the same plane with the axis of the roll between that of the motor shaft and lighter bar pivots.

Transverse struts 192 extend between the side walls 2 and 4 and are secured by welding to the said walls and the platform 164, see Fig. 4.

An upper transverse wall 196 extends between and has opposite ends welded to the side walls 2 and 4. Said wall has a vertical lip portion 198 and a portion 200 extending upwardly and forwardly therefrom and then downwardly and terminates in a substantially horizontal portion 202, see Fig. 4.

An inlet member 204 extends through the platform 164 and is secured to said platform, to the member 192 adjacent thereto and to portion 200 of the upper wall by welding. Said inlet has an opening 206 and a portion 208 thereof is spaced from the lip 198 to provide a narrow passageway 210. The opening 206 may be connected to a water supply whereby washing may be accomplished through the passageway 210.

As in Fig. 4, the upper end flange 104 of the cover 100 is secured to member 208.

A back-fall wall 212 extends between the walls 2 and 4 and has its opposite ends and lower end portions secured to said walls and the sole plates 6 and 8 by welding.

The lighter-bar caps 88 are provided with eyes 214 to which tackle may be attached for assembling and disassembling purposes and likewise, although not shown, the cover or hood 100 may be provided with eyes.

As will be seen, the sole plates, front and mid-wall and various transversely extending walls secured together as they are provide a strong rigid structure with which the lighter-bar pillars, and adjusting mechanism is integral and in which the equalizer shaft and lighter bars are

mounted and the various components operatively connected and maintained in accurate alignment and operative relationship.

Thus there is provided a unitary, self-contained beater-refiner mechanism adapted for shipment to the mill of the purchaser. Inasmuch as the components are tied together in a unitary structure and in operative relationship no special foundation structures are necessary for aligning and tying the components for their operation. The structure may be set on any support suitable for supporting the same and it is unnecessary to dispatch erectors to the destination of the mechanism since the purchaser need only set the mechanism on a support and construct the beater tub around and in conjunction with the mechanism.

As previously stated, it may be desired to employ plural units in a manner to perform a continuous process or successive steps in a process in which case the purchaser may arrange the mechanisms as desired and construct the cooperating apparatus.

Where the mechanism is to be used in connection with a beater tub, the mid-wall 4 may function as the mid-feather and beater walls may extend from the forward wall 2. The front bottom wall of the beater may extend from the right hand side of the channel 24 of lower transverse wall 20 and the back-fall may extend downwardly and to the left from the upper end of intermediate wall 14 as seen in Fig. 4.

The roll 40 will be rotated in the direction of the arrow in Fig. 4 for coaction of the knives of said roll and of the bed plate. Any relatively heavy objects in the material, particularly metal objects, such as bolts, nuts and the like, will be thrown by the roll into the transverse channel 24 thereby eliminating the possibility of injury to the knives or bars of the roll and bed plate.

The invention may be embodied in other specific forms without departing from the essential characteristics thereof. Hence, the present embodiments are therefore to be considered in all respects merely as being illustrative and not as being restrictive, the scope of the invention being indicated by the appended claims rather than by the foregoing description, and all modifications and variations as fall within the meaning and purview and range of equivalency of the appended claims are therefore intended to be embraced therein.

What it is desired to claim and secure by Letters Patent of the United States is:

1. A unitary self-contained transportable beater-refiner construction adapted for association with a beater tub or the like comprising in combination, transversely spaced elongated horizontal sole plates and front and mid-walls having longitudinal lower edges secured to said sole plates by welding and extending vertically and upwardly therefrom, upper back-fall and front plate members with a bed-plate base therebetween having corresponding opposite ends fixed to said walls so as to be integral therewith, said upper back-fall and front plate members having adjacent relatively spaced portions secured to opposite ends of said bed-plate base, relative spaced partitions above said bed-plate base between and spaced from said portions having opposite ends fixed to said walls and lower edges fixed to bed-plate base so as to be integral therewith and provide a plurality of pockets for bed-plate boxes, pillars for lighter bars at outer sides of said walls fixed thereto and

5 to said sole plates and extending upwardly vertically relative thereto, lighter-bars having inner ends pivoted to said pillars extending therefrom and having journal means for a roll between said inner ends and forward ends thereof, a transverse equalizer shaft extending through said walls and oscillatable in bearing means secured to said walls, operative connections between outer ends of said lighter-bars and equalizer shaft for corresponding uniform movements of said lighter bars, adjusting means fixed to one of said sole plates adjacent an outer side of one of said walls, and operative connections between said adjusting means and the outer end of one of said lighter-bars, each of said pillars having outer walls fixed at lower ends to said sole plates by welding and adjacent upwardly converging side walls fixed at lower and inner edges to said sole plates and adjacent walls by welding and horizontally spaced vertically extending pivot mounting members fixed to said outer and side walls and to a horizontal wall fixed to said outer and side walls.

2. A unitary self-contained transportable beater-refiner construction adapted for association with a beater tub or the like comprising in combination, transversely spaced elongated horizontal sole plates and front and mid-walls having longitudinal lower edges secured to said sole plates by welding and extending vertically and upwardly therefrom, upper back-fall and front plate members with a bed-plate base therebetween having corresponding opposite ends fixed to said walls so as to be integral therewith, said upper back-fall and front plate members having adjacent relatively spaced portions secured to opposite ends of said bed-plate base, relative spaced partitions above said bed-plate base between and spaced from said portions having opposite ends fixed to said walls and lower edges fixed to bed-plate base so as to be integral therewith and provide a plurality of pockets for bed-plate boxes, pillars for lighter bars at outer sides of said walls fixed thereto and to said sole plates and extending upwardly vertically relative thereto, lighter-bars having inner ends pivoted to said pillars extending therefrom and having journal means for a roll between said inner ends and forward ends thereof, a transverse equalizer shaft extending through said walls and oscillatable in bearing means secured to said walls, operative connections between outer ends of said lighter-bars and equalizer shaft for corresponding uniform movements of said lighter bars, adjusting means fixed to one of said sole plates adjacent an outer side of one of said walls, and operative connections between said adjusting means and the outer end of one of said lighter-bars, each of said pillars having outer walls fixed at lower ends to said sole plates by welding and adjacent upwardly converging side walls fixed at lower and inner edges to said sole plates and adjacent walls by welding and horizontally spaced vertically extending pivot mounting members fixed to said outer and side walls and to a horizontal wall fixed to said outer and side walls, and U-shaped reinforcing members having lower transverse portions welded to said sole plates and horizontally spaced side arm portions extending upwardly therefrom between and welded to the walls of said pillars.

3. A unitary self-contained transportable beater-refiner construction adapted for association with a beater tub or the like comprising in combination, transversely spaced elongated horizon-

tal sole plates and front and mid-walls having longitudinal lower edges secured to said sole plates by welding and extending vertically and upwardly therefrom, upper back-fall and front plate members with a bed-plate base therebetween having corresponding opposite ends fixed to said walls so as to be integral therewith, said upper back-fall and front plate members having adjacent relatively spaced portions secured to opposite ends of said bed-plate base, relative spaced partitions above said bed-plate base between and spaced from said portions having opposite ends fixed to said walls and lower edges fixed to bed-plate base so as to be integral therewith and provide a plurality of pockets for bed-plate boxes, pillars for lighter bars at outer sides of said walls fixed thereto and to said sole plates and extending upwardly vertically relative thereto, lighter-bars having inner ends pivoted to said pillars extending therefrom and having journal means for a roll between said inner ends and forward ends thereof, a transverse equalizer shaft extending through said walls and oscillatable in bearing means secured to said walls, operative connections between outer ends of said lighter-bars and equalizer shaft for corresponding uniform movements of said lighter bars, adjusting means fixed to one of said sole plates adjacent an outer side of one of said walls, and operative connections between said adjusting means and the outer end of one of said lighter-bars, each of said pillars having outer walls fixed at lower ends to said sole plates by welding and adjacent upwardly converging side walls fixed at lower and inner edges to said sole plates and adjacent walls by welding and horizontally spaced vertically extending pivot mounting members fixed to said outer and side walls and to a horizontal wall fixed to said outer and side walls, corresponding end portions of said front and mid-walls at outer sides thereof provided with horizontally spaced vertically extending pilasters welded thereto, and a platform for drive means on the upper edges of said walls and pilasters and fixed thereto.

4. A unitary self-contained transportable beater-refiner construction adapted for association with a beater tub or the like comprising in combination, transversely spaced elongated horizontal sole plates and front and mid-walls having longitudinal lower edges secured to said sole plates by welding and extending vertically and upwardly therefrom, upper back-fall and front plate members with a bed-plate base therebetween having corresponding opposite ends fixed to said walls so as to be integral therewith, said upper back-fall and front plate members having adjacent relatively spaced portions secured to opposite ends of said bed-plate base, relative spaced partitions above said bed-plate base between and spaced from said portions having opposite ends fixed to said walls and lower edges fixed to bed-plate base so as to be integral therewith and provide a plurality of pockets for bed-plate boxes, pillars for lighter bars at outer sides of said walls fixed thereto and to said sole plates and extending upwardly vertically relative thereto, lighter-bars having inner ends pivoted to said pillars extending therefrom and having journal means for a roll between said inner ends and forward ends thereof, a transverse equalizer shaft extending through said walls and oscillatable in bearing means secured to said walls, operative

connections between outer ends of said lighter-bars and equalizer shaft for corresponding uniform movements of said lighter bars, adjusting means fixed to one of said sole plates adjacent an outer side of one of said walls, and operative connections between said adjusting means and the outer end of one of said lighter-bars, each of said pillars having outer walls fixed at lower ends to said sole plates by welding and adjacent upwardly converging side walls fixed at lower and inner edges to said sole plates and adjacent walls by welding and horizontally spaced vertically extending pivot mounting members fixed to said outer and side walls and to a horizontal wall fixed to said outer and side walls, corresponding end portions of said front and mid-walls at outer sides thereof provided with horizontally spaced vertically extending pilasters welded thereto, and a platform for drive means on the upper edges of said walls and pilasters and fixed thereto.

5. A unitary self-contained transportable beater-refiner construction adapted for association with a beater tub or the like comprising in combination, transversely spaced elongated horizontal sole plates and front and mid-walls having longitudinal lower edges secured to said sole plates by welding and extending vertically and upwardly therefrom, upper back-fall and front plate members with a bed-plate base therebetween having corresponding opposite ends fixed to said walls so as to be integral therewith, said upper back-fall and front plate members having adjacent relatively spaced portions secured to opposite ends of said bed-plate base, relative spaced partitions above said bed-plate base between and spaced from said portions having opposite ends fixed to said walls and lower edges fixed to bed-plate base so as to be integral therewith and provide a plurality of pockets for bed-plate boxes, pillars for lighter bars at outer sides of said walls fixed thereto and to said sole plates and extending upwardly vertically relative thereto, lighter-bars having inner ends pivoted to said pillars extending therefrom and having journal means for a roll between said inner ends and forward ends thereof, a transverse equalizer shaft extending through said walls and oscillatable in bearing means secured to said walls, operative connections between outer ends of said lighter-bars and equalizer shaft for corresponding uniform movements of said lighter-bars, adjusting means fixed to one of said sole plates adjacent an outer side of one of said walls, and operative connections between said adjusting means and the outer end of one of said lighter-bars, each of said pillars having outer walls fixed at lower ends to said sole plates by welding and adjacent upwardly converging side walls fixed at lower and inner edges to said sole plates and adjacent walls by welding and horizontally spaced vertically extending pivot mounting members fixed to said outer and side walls and to a horizontal wall fixed to said outer and side walls, corresponding end portions of said front and mid-walls at outer sides thereof provided with horizontally spaced vertically extending pilasters welded thereto, and a platform for drive means on the upper edges of said walls and pilasters and fixed thereto.
